UNITED STATES PATENT OFFICE

159,478

DECK OF PLAYING CARDS

Kathryn B. Ewbank, Norman, Okla.

Application July 29, 1948, Serial No. 147,815

Term of patent 14 years

(Cl. D34—13)

To all whom it may concern:

Be it known that I, Kathryn B. Ewbank, a citizen of the United States, residing at Norman, in the county of Cleveland and State of Oklahoma, have invented a new, original, and ornamental Design for a Deck of Playing Cards, of which the following is a specification, reference being had to the accompanying drawing, forming part thereof.

In the drawings:

Fig. 1 is a face view of the single joker card of the deck of playing cards, showing my new design;

Figs. 2 to 14 inclusive are face views of the thirteen cards in each suit of the deck of playing cards;

The four suits in the deck of playing cards differ from each other in color only. The total number of cards in the deck is 53.

I claim:

The ornamental design for a deck of playing cards, as shown and described.

KATHRYN B. EWBANK.
